UNITED STATES PATENT OFFICE.

THOMAS E. MURRAY, OF NEW YORK, N. Y.

METHOD OF FORMING INTEGRAL FLANGES ON BODIES OF DUCTILE METAL.

1,036,509.

Specification of Letters Patent. Patented Aug. 20, 1912.

Application filed March 28, 1912. Serial No. 686,812.

To all whom it may concern:

Be it known that I, THOMAS E. MURRAY, a citizen of the United States, residing at New York, in the county of New York and State of New York, have invented a certain new and useful Improvement in Methods of Forming Integral Flanges on Bodies of Ductile Metal, of which the following is a specification.

10 The invention is a method of forming a flange upon a pipe, sheathing, rod or other elongated body of ductile metal having the quality of integrally uniting by pressure when cold such as lead—which flange, 15 among other special purposes, may serve as means for closing a joint between the pipe, sheathing or rod and any object receiving the same, or through which the same may pass.

20 In the accompanying drawings—Figure 1 is a sectional view of an electric conductor, having a lead sheathing, upon which sheathing the flange is formed, showing the mode of causing the material of the flange to weld 25 or cohere to the material of the sheathing.

Fig. 2 is a similar view, showing the mode of consolidating the material of the flange. Fig. 3 is a similar view, showing the completed flange in its receptacle, and Fig. 4 30 shows the sheathed conductor with the flange formed thereon separate from the receptacle and in perspective.

Similar letters of reference indicate like parts.

35 My method is herein illustrated by the formation of a lead flange on the lead sheathing A of an electrical line conductor B, provided with the usual insulating envelop C. It is, of course, to be understood, that any 40 other elongated body of ductile metal having the quality of integrally uniting by pressure when cold—such as a lead pipe—is within my invention. In order to form the flange, I insert the conductor B through an 45 opening in a block D, in which is a cavity E, the depth and diameter of which may determine the size of the flange. I then place in the bottom of the cavity a quantity of lead filaments F of the same metal—commonly known as lead floss—and by means of a tapered tool G, I force the floss immediately adjacent to the lead sheathing into cohesion therewith, so that the consolidated floss and the sheathing become practically

integral. I then, with a wider nosed tool H, consolidate the floss elsewhere in the cavity, as shown in Fig. 2. As soon as one layer of floss is thus caused to cohere and unite integrally with the sheathing and is consolidated, I introduce another layer into 60 the cavity and repeat the operation, and thus continue adding successive layers until the flange is completed.

The conductor with the flange I formed thereon and integral therewith, may then, 65 if desired, be removed from the block D. In such event, the block D serves only as a mold for the flange. But instead of making the cavity in block D, I may make it in any object in which the conductor or pipe 70 is to be permanently secured, as, for example, a coupling sleeve in the case of the pipe, or a junction box or insulator in case of the sheathed conductor. The flange I then remains permanently in the object and 75 closes the joint.

I claim:

1. The method of forming an annular flange integrally with and upon an elongated body of ductile metal having the 80 quality of integrally uniting by pressure when cold, which consists in inserting said body into a mold having a cavity of predetermined diameter and depth, introducing a mass of floss of said metal into said cavity, 85 causing the same to cohere with and around said body, and consolidating the remainder of said mass.

2. The method of forming an annular flange integrally with and upon an elongated body of ductile metal having the 90 quality of integrally uniting by pressure when cold, which consists in inserting said body into a mold having a cavity of predetermined diameter and depth, introducing a mass of floss of said metal into said cavity, 95 partially to fill the same, causing said mass to cohere with and around said body, consolidating the remainder of said mass, introducing a second mass of floss and 100 repeating the operation, and so on successively until said flange is completed.

In testimony whereof I have affixed my signature in presence of two witnesses.

THOMAS E. MURRAY.
